LAMP

Richard M. Del Orsinee, Fox Lake, Wis., assignor to La Della Art Studios, Fox Lake, Wis., a partnership

Application November 23, 1953, Serial No. 27,708

Term of patent 14 years

(Cl. D48—20)

To all whom it may concern:

Be it known that I, Richard M. Del Orsinee, a citizen of the United States of America, residing at 207 State Street, Fox Lake, in the county of Dodge and State of Wisconsin, have invented a new, original, and ornamental Design for a Lamp, of which the following is a specification, reference being had to the accompanying drawing, forming part hereof.

In the drawing:

Fig. 1 is a front perspective view of a lamp showing my new design.

Fig. 2 is a rear perspective view thereof.

Fig. 3 is a side elevational view partly in section.
Fig. 4 is a top plan view partly in section.

I claim:

The ornamental design for a lamp, as shown.
